UNITED STATES PATENT OFFICE.

ERNEST OTTO MARSH, OF SEATTLE, WASHINGTON.

TROLLEY-EAR CLENCHER.

No. 877,510.

Specification of Letters Patent.

Patented Jan. 28, 1908.

Application filed September 27, 1906. Serial No. 336,505.

To all whom it may concern:

Be it known that I, ERNEST OTTO MARSH, a citizen of the United States, residing at Seattle, in the county of King, State of Washington, have invented certain new and useful improvements in Trolley-Ear Clenchers; and I do hereby declare the following to be a full, clear, and exact description of the invention, such as will enable others skilled in the art to 10 which it appertains to make and use the same.

This invention has relation to means for clenching the pendent margins of a trolley-wire ear, when arranged over the wire, around the sides and bottom of the said wire, bringing the edges together, or as nearly together as the conditions may require.

The nature of the invention embodies a device, termed by me a "clencher" that is adapted to be moved with requisite force against 20 the projecting margins of a trolley-wire ear, arranged over or about the wire, and by reason of the form of the surface coming into contact with said margins of the ears, clench or close the same on the wire, the ear and wire 25 being suitably held or supported on the side opposite to the clencher to allow the latter to perform its stated functions.

The invention is shown as embodied in the means illustrated in the annexed drawings, 30 forming a part of this specification, in view of which it will be described with respect to its construction and mode of operation and then be pointed out in the subjoined claims.

Of the said drawings, Figure 1 is a longitudinal central vertical section of a device embodying my invention, showing it as in position of completing the clenching of the ear on the wire. Fig. 2 is a transverse section of the means represented in Fig. 1 and showing, in 40 addition, the ear and wire about which the ear is clenched. Fig. 3 is a modified view of means for operating the clencher. Fig. 4 is a transverse section showing the position of the ear and wire relative to the other parts before 45 the operation of clenching is effected.

Similar figures of reference designate similar parts or features, as the case may be, wherever they occur.

In the drawings, 10 designates the casing, 50 constructed and arranged to have the clencher 11 move therein, the said casing being made in two parts, connected by bolts or screws 12 extended through holes formed through projecting lugs or swells 13 formed on the ends of 55 the casing. Furthermore, the said casing is

provided on the upper edges of its extended sides with resilient clamps or holders 14 that are constructed with inward and downwardly beveled margins, adapted to be moved upward against the sides of the portion of the 60 ears astride of the wires, springing apart in so doing to engage the upper sides of that portion 15 of the trolley ear 16 and hold the wire and the said portion of the ears astride of the same firmly against upward movement, and 65 support the same against being moved laterally.

The upper surface 18 of the clencher 11 is given such form that when it is forced against the lower edges 19 of the trolley ear, from the 70 position shown in Fig. 4 to that in which it is represented in Fig. 2, it will turn the same inward about the wire, bringing said edges together or nearly together, as shown in said Fig. 2. In the drawings, the said upper surface of the clencher is shown as being of concave form or having inclined sides and a base or center to serve as a kind of anvil to press the inturned edges of the ears against the wire the ears and wire being held firmly down 80 by the offsets forming the hooks of the holding means 14. Any other form of surface that will accomplish the described ends will answer as well as that shown.

As a means for operating the clencher to 85 effect the work of clamping the sides of the trolley ear about the wire, as described, I may employ toggle levers 20—21 on each side of the clencher pivotally connecting the inner ends of the said levers at their knee 90 joint 22, pivoting the upper ends of the members 20 on the clencher 11, as at 23, and pivoting the lower member 21 on the pins 24 supported in the casing. The lower arms 25 of the levers 21 are extended through openings 95 in the casing and are movable in said openings so as to bring them toward each other or in substantially parallel position vertically and so substantially straighten the toggle levers 20 and 21, moving up the clencher 100 with powerful force against the edge 19 of the trolley-wire ear 16 and clenching said edges as before described, and as shown in Fig. 2. By separating the lower arms 25 of the levers 21, the knee joint of the toggle levers will 105 be bent or broken and the clencher drawn down, all as will be entirely understood without further description.

The clencher is provided centrally with guide slots 26 on its sides into which a guide 110

27, constructed as a rib on opposite sides of the casing, may enter, as the clencher is reciprocated to maintain the latter in true position.

5 Instead of employing toggle levers to reciprocate the clencher, as shown in Fig. 1, I may form teeth 28 on the sides of the central pendent portions of the clencher opposite the guide slot 26 and provide the upper inner 10 arm of the lever 21 with teeth 29 suited to engage the teeth 28, so that by moving the arm 25 of the latter lever, as before described, the said clencher may be operated precisely as before set forth.

15 In preparing for clenching operation, the trolley-wire ear 16 will be secured to its hanger and arranged over the wire and the clencher will be engaged with the wire at one side of the ear, and then moved along the 20 latter over the ear when the clencher may be actuated to effect the clenching as hereinbefore indicated. But a portion of the ear may be clenched on the wire at one time, the clencher being moved along from place to 25 place until the work of clenching is completed.

It is recognized that the device shown may be altered or changed in the form and arrangement of its parts and features without 30 departing from the general nature or spirit of the same.

What is claimed in the invention, is:—

1. A trolley-ear clencher comprising a casing open at the top and the sides of its upper edges formed as clamps to engage the sides of 35 the ear astride of the wire and hold the same rigidly, a movable clencher supported and guided by the casing and having a concave upper edge, and means connected with the casing for moving the clencher upward 40 against the edges of the ear held by the clamp and close or crimp the same closely around the wire.

2. A trolley-ear clencher comprising a casing open at the top and the sides of its upper 45 edges formed as clamps to engage the sides of the ear astride of the wire and hold the same rigidly, a movable clencher supported and guided by the casing and having a concave upper edge, and toggle-levers pivoted on the 50 casing and clencher and means for operating the said toggle-levers, for moving the clencher upward against the edges of the ear held by the clamp and close or crimp the same closely around the wire.

55 In testimony whereof, I affix my signature, in presence of two witnesses.

ERNEST OTTO MARSH.

Witnesses:

JAMES B. DOWD,
P. C. DORMITZER.
